UNITED STATES PATENT OFFICE.

JOSEPH J. DOLYAK, OF YOUNGSTOWN, OHIO.

MOLD.

1,265,438.

Specification of Letters Patent.

Patented May 7, 1918.

Application filed March 2, 1918. Serial No. 220,084.

To all whom it may concern:

Be it known that I, JOSEPH J. DOLYAK, a citizen of the United States, residing at Youngstown, in the county of Mahoning and State of Ohio, have invented certain new and useful Improvements in Molds, of which the following is a specification, reference being had to the accompanying drawings.

This invention relates to molds, and has for its primary object to provide a mold for producing building blocks of cementitious or plastic materials which is of such construction that the various parts thereof can be easily and quickly set up in operative position, or disassembled for the removal of the molded block.

It is a more particular object of the invention to provide a block mold having two body sections each including a longitudinal wall and an end wall, the walls of said sections when assembled having interfitting engagement at their ends, and means for effectively clamping the walls of the mold and holding the same against relative movement from their assembled positions by the pressure of material poured into the mold.

And it is a further general object of my invention to provide a block mold as above characterized, the several parts of which are of very simple form so that the mold as a whole can be produced at relatively small manufacturing cost.

With the above and other objects in view the invention consists in the improved combination, construction and arrangement of the several parts as will be hereinafter more fully described, subsequently claimed and illustrated in the accompanying drawing in which similar reference characters designate corresponding parts throughout the several views and wherein.

Figure 1 is a top plan view showing a mold assembled and the top or cover plate thereof removed.

Fig. 2 is a side elevation;

Fig. 3 is an enlarged horizontal section through one corner of the mold taken on the line 3—3 of Fig. 2; and

Fig. 4 is a plan view of one of the clamping bars.

Referring in detail to the drawing, 5 designates two sections of the mold which are of similar construction and each of which includes a longitudinal side wall 6 and an end wall 7, the mold sections being substantially L-shaped in plan. Upon the outer face of

the walls 6 and 7 of each mold section a longitudinally extending rib designated 8 and 9 respectively is formed. These ribs are integral with each other at the corner of the mold section but terminate in spaced relation to the opposite ends of the mold walls. The ends of the mold walls are rabbeted on their inner faces, as at 10, whereby tongues and grooves are provided for interfitting engagement when the two sections of the mold are set up or assembled, as seen in Fig. 1.

11 designates a base plate which is provided upon one face with a continuous flange or rib 12 in spaced relation to the marginal edges of the plate to support the base plate above the ground or floor surface. Upon this base plate, the body sections of the mold are assembled. Clamping bars generally designated by the numeral 13 are then applied to the exterior of the mold walls adjacent their upper and lower edges. Each of these clamping bars is of the form shown in Fig. 4 and includes the part 14 to extend along the longitudinal wall of one mold section and the angularly extending part 15 which is disposed across the end wall of the mold section. Each of these parts 14 and 15 of the clamping bar terminates in an angularly disposed arm indicated at 16, and these arms are adapted to engage over the ends of the longitudinal and end walls of the other mold section, as will be readily understood from reference to Fig. 1 of the drawing. At the rabbeted interfitting ends of the mold walls, wedge elements, shown at 17, are driven downwardly between the inner edges of the clamping bar and the side and end walls of the two mold sections, whereby the latter are tightly clamped together at their abutting ends and separation of the same resulting in leakage of the plastic material poured into the mold is thereby obviated.

In addition to the bars 13, clamping elements 18 are provided each of which consists of a relatively short rod or bar having lugs 19 on its ends projecting at right angles to the bar and in parallel relation to each other. These clamping elements are of requisite length so that their lugs may be engaged under the marginal edges of the base plate 11 and over the ribs 8 and 9 formed upon the walls of the mold sections. Additional webs shown at 20 are then driven horizontally between the lugs 19 on the upper ends of the clamping members and the ribs 8 and 9, whereby the walls of the mold sections are

2
tightly clamped and held against shifting movement upon the base plate 13.

Having set up the mold and securely clamped its walls together in the manner above explained, the plastic material from which the block is to be formed is then poured into the space bounded by the mold walls. It will be manifest that this space can be of any desired dimensions and the inner faces of the mold walls may be roughened, corrugated or otherwise fashioned to produce a block of ornamental form. Preferably, I provide a top or cover 21 for the mold which is placed upon the upper edges of the mold walls after the plastic material has been poured. This cover is of the same construction as the base plate 11 and is also provided with a continuous flange or rib 22 in spaced relation to its marginal edges. Bails or handle members indicated at 23 may be suitably secured to this flange at the opposite ends of the cover plate whereby it can be conveniently arranged in place upon the mold walls or removed therefrom. From the foregoing description taken in connection with the accompanying drawings, the construction, manner of use, and several advantages of my improved mold, will be clearly and fully understood. The various parts are of exceedingly simple form, as well as strong and durable. The mold as a whole may be manufactured at relatively small cost and is admirably adapted for use in the production of blocks formed from cement or other plastic material such as are generally used for building purposes. In the foregoing description, I have referred to a preferred construction of the clamping members as well as the mold walls, but it will be understood that in practice these details of the device may be considerably varied in their form and proportion as particular conditions or circumstances may require. Accordingly, I reserve the privilege of adopting all such legitimate changes of which the device may be susceptible as may be fairly embraced within the spirit and scope of the invention as claimed.

Having thus fully described my invention, what I desire to claim and secure by Letters Patent is:

1. In a mold, two mold sections each having one side and one end wall, clamping members adapted for engagement exteriorly with the side and end walls of the respective sections adjacent their relatively opposite edges and having terminal arms to extend upon the walls of the other mold section,

and wedges insertible between said clamping members and the mold walls to clamp the walls together at their abutting ends.

2. In a mold, two body sections each having a side wall and an end wall, said walls being rabbeted at their ends for interfitting engagement with the mold sections when assembled, clamping bars having angular portions for engagement upon the exterior faces of the walls of the respective mold sections adjacent their relatively opposite edges, each of said bars terminating in angularly extending arms for engagement upon the ends of the walls of the other mold section, and clamping wedges insertible between the inner edges of said bars and the mold walls to hold the bars in assembled relation and clamp the walls together against relative movement.

3. In a mold, two mold sections each having a side and an end wall, a base plate upon which said mold sections are adapted to be assembled, means for clamping the sections together in assembled relation, and additional means for clamping the mold sections upon said base and holding them against movement relative thereto.

4. In a mold, two mold sections each having a side and an end wall provided upon its outer face with a longitudinally extending rib, a base upon which the mold sections are adapted to be assembled, means for retaining the mold sections in assembled relation, and clamping means for operative engagement with the ribs on the mold walls and with said base to clamp the mold sections against shifting movement with respect to the base.

5. In a mold, a supporting base, mold walls adapted to be assembled upon said base, each of said walls having a longitudinally extending rib formed on its outer face, clamping bars having angularly disposed terminal lugs for engagement beneath the marginal edges of the base and over the ribs on the mold walls respectively, and wedge elements adapted to be driven between the terminal lugs on the upper ends of the clamping bars and said ribs whereby the mold walls are clamped upon the base and held against shifting movement relative thereto.

In testimony whereof I hereunto affix my signature in the presence of two witnesses.

JOSEPH J. DOLYAK.
